(57) **CLAIM**

The ornamental design for a wearable electronic device, as shown and described.

DESCRIPTION

FIG. 1 is a front perspective view of a wearable electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is another front view thereof mounted on a helmet. The broken lines in FIG. 8 showing the helmet depict environmental subject matter only and form no part of the claim, while all other broken lines depict portions of the electronic device that form no part of the claimed design. The claim extends to the innermost shade line in FIG. 3, but does not include any unshaded surfaces beyond these shade lines.
